BAIL SUPPORT FOR CARPET SWEEPERS

Robert S. Wagner, Milwaukee, Wis., assignor to
 E. R. Wagner Manufacturing Company, Milwaukee, Wis., a corporation of Wisconsin

Application March 28, 1946, Serial No. 657,856

4 Claims. (Cl. 306—11)

1

This invention relates to improvements in carpet sweepers and particularly to supports for handle bails.

There are two purposes of a support for a bail. It holds the bail and handle in an upright position when the carpet sweeper is not in use. When the sweeper is operated, the support engages the bail and exerts a stabilizing action preventing the end of the sweeper from rocking upwardly at the end of a forward stroke or during the return stroke. Because of this the bail and support are subject to excessive wear and in the constructions heretofore used either the legs of the bail were worn and substantially cut through, or the protuberances struck from the end brackets which constituted the supports were worn off, or both such conditions occurred materially shortening the efficient life of the sweeper.

It is an object of this invention, therefore, to provide support for a bail which will be efficient throughout the useful life of the sweeper.

Another object of this invention is to provide a support for a bail which is simple in construction and is easily and inexpensively manufactured.

These objects are obtained by making the support from a flat rectangularly shaped piece of phosphor bronze curved longitudinally and provided intermediate its ends with two spaced wave-like humps. The support is positioned with its ends held between the end of the casing and the end bracket and the humps protruding outwardly through an opening in the end bracket. The curved surfaces of the humps engage the inner surfaces of the bail legs as the bail and handle are moved from sweeping to vertical position relative to the case. During such relative movements there is some give in the support and some spreading apart of the bail legs to permit the legs to ride up and over the humps. However, due to the size of the contacting surfaces of the humps and bail legs and the fact that the legs are steel and the support is phosphor bronze, any harmful wear is eliminated and the efficient life of the bail and support is as great as that of the sweeper.

The novel features, which are considered characteristic of the invention are set forth with particularity in the appended claims. The invention itself, however, both as to its organization and its method of operation, together with additional objects and advantages thereof, will best be understood from the following description of a specific embodiment when read in connection with the accompanying drawing, in which:

2

Figure 1 is an end view in side elevation of a carpet sweeper embodying the invention with the end bell broken away for the sake of clarity in illustration;

5 Figure 2 is an enlarged fragmentary view of the support for the bail and bracket plate; and

Figure 3 is a sectional view taken on the meandering section line 3—3 of Figure 2.

Referring to the drawings by reference numerals, the support for the bail is shown incorporated in a carpet sweeper having a casing 10 provided with the usual wooden end walls 11 and metal cover 12. The cover 12 is formed with flanges 13 which overlap the marginal sides of the walls 11. A bracket plate 14 screwed to the end wall 11 provides support for the wheels 15 and the bail 18. As is customary, the plate 14 has a brush-receiving recess 16 which accommodates the shaft of the brush 28. The brush 28 is of standard construction and is carried by the carpet sweeper in a manner well known to those skilled in the art. A handle 17 is detachably carried by a bail 18. The bail 18 has vertical legs 19, the lower ends of which are inturned to form bearing axles 20. The bracket plate 14 is provided with an opening constituting a bearing 21 for the axles 20. This opening may be made by piercing and leaving a surrounding flange to increase the bearing area. The area around the upper three-quarters of the bearing 21 is raised above the surface of plate 14 as indicated at 22 to provide a bearing surface against which the legs 19 laterally press. This raised area also provides a recess on the inner side of the plate 14 which receives therein the legs 26 of the support 24. There is an opening 23 in this area which permits the humps 27 of the support 24 to project laterally from the plate 14 as is shown in Figure 3.

The support 24 is preferably formed from a flat sheet or ribbon of phosphor bronze designated commercially as Grade A. It is curved longitudinally so that its sides lie substantially on the arcs of concentric circles. It has a flat center portion 25 and two flat extending legs 26.

45 Intermediate the center portion 25 and each leg 26 is formed a wave-like hump 27. The distance of the tops of these humps 27 from the surface of the center 25 and legs 26 is sufficient to project through the slot 23 beyond the surface of area 22 and protrude into the path of travel of the legs 19. The longitudinal axis of the humps 27 lie substantially parallel to radii passing through the center of the bearing 21. This provides them with curved surfaces which engage the inner surface of the legs 19 over a substantial area to pro-

vide good bearing surface therebetween. The support 24 is loosely held in place between the plate 14 and the flanges 13, as shown in Figure 3, so that when the bail 18 is swung upwardly from the position shown in Figure 1 the leg 19 will press against the hump 27 and act as a stabilizer preventing the opposite end of the sweeper from raising at the end of a stroke and during the return stroke. As the bail is continued in its upward movement its leg 19 will ride over the first hump 27 and it will thereafter be engaged by both humps 27 and retained in vertical position. In passing over a hump there will probably be some give in the support 24 as well as a spreading apart of the legs. However, the spring action on the part of the support 24 is not necessary as there is plenty of spring action in the bail itself.

It is preferable and economical that the bail 18 be formed of what is commonly known as cold rolled steel. It has been found that the sliding engagement between the bail legs 19 and the holder 24 will not wear away the inner surface of the legs 19 or appreciably wear away the tops of the humps 27. In some instances after severe use there may be found on the inside of the leg 19 a small film or deposit of the bronze from support 24.

Although only one embodiment of the invention is shown and described herein, it will be understood that this application is intended to cover such changes or modifications as come within the spirit of the invention or scope of the following claims.

I claim:

1. In a carpet sweeper, a casing having an end, a bracket plate carried on said end, a bail pivotally mounted to said bracket, a bail support having portions engaged between said end and said plate, and a wave-like hump in said support between said portions projecting laterally through said plate with its convex portion engageable with the leg of said bail in selected positions thereof.

2. In a carpet sweeper, a bracket plate having an aperture, a raised portion adjacent said aperture, a slot in said raised portion, a bail having a leg in sliding engagement with said raised portion and an inturned end pivotally mounted in said aperture, and a bail support having a pair of spaced wave-like humps projecting through said slot into the path of travel of said leg, said support having portions loosely engaging the under-surface of said plate to maintain said support in position.

3. In a carpet sweeper, a casing having a metal cover with down-turned flanges at its ends, a bracket plate carried by said casing and overlying a portion of said flanges, said plate having a recess in its inner surface, an opening adjacent said recess, a bail pivotally carried by said plate and having a portion movable over said opening, and a support for holding said bail in selected position, said support having a wave-like hump projecting through said opening into the path of travel of said portion and a holding leg positioned in said recess and held therein by said flange.

4. In a carpet sweeper, a casing having an end wall, a bracket plate having an aperture constituting a bearing for the axle of a bail, there being a curved opening in said plate partially surrounding and closely adjacent said aperture, said opening being adapted to receive the raised portions of a bail support, a bail support comprising a flat piece of metal having a curved bottom edge fitting around said bearing, there being formed from said support between the flat parts thereof and adjacent said bottom edge a pair of raised portions, said raised portions being curved to conform with and project through said curved opening, said portions being centrally separated by a lower portion to form opposed surfaces for gripping the leg of a bail in vertical position, said bail support having its flat portions placed between said plate and said end wall to maintain said raised portions in projecting relationship through said curved opening and in the path of travel of a bail leg, and a bail having an axle pivoted in said bearing and a leg movable over the surface of said plate in engagement with said projecting raised portions.
